CAP FOR A JUG OR THE LIKE

Harold J. Vanderhyde, North Merrick, N.Y., assignor to The Procter & Gamble Company, Cincinnati, Ohio, a corporation of Ohio

Filed Jan. 11, 1967, Ser. No. 5,388

Term of patent 14 years

(Cl. D9—285)

FIG. 3

FIG. 4

FIG. 1 is an elevational view of a cap for a jug or the like, showing my new design.

FIG. 2 is a top plan view of the same.

FIG. 3 is a cross sectional view of the same taken on the line 3—3 of FIG. 1.

FIG. 4 is a cross sectional view of the same taken on the line 4—4 of FIG. 1.

I claim:

The ornamental design for a cap for a jug or the like, as shown.
